REFRIGERATED SHOW CASE

Application filed February 26, 1931. Serial No. 518,535.

This invention relates to refrigerated showcase, and has for its object the provision of means for catching the drip from the moisture condensing on the refrigerating coil so as to prevent its falling upon the refrigerated objects in the showcase, said means being constructed to present the minimum interference to the convection circulation within the refrigerated chamber.

10 It is known at the present time that by using a cross fin coil with vertical fins of aluminum having an aggregate area substantially that of the bounding surfaces of the refrigerated chamber in a well insulated showcase, in a focal position in said showcase, a convection circulation is set up and maintained, so efficient that the refrigerating coil can be run at a temperature so slightly below the showcase temperature that no condensation will occur on the fins or tubes of the coil.

In those installations in which the coil extends from one end to the other of the showcase along the top of the refrigerated chamber the convection circulation is somewhat interfered with by the longitudinally distributed down drift of cold air from the coil, so that it becomes necessary to run the coil at a lower temperature in order to realize the same degree of refrigerating temperature in the showcase. The range between the coil temperature and the temperature of the surrounding air within the refrigerated chamber is then so wide as to produce condensation on the fins or tubes of the coil in the form of dew. The drip of the condensate would without suitable preventive provision fall upon the products on the shelves below, in the refrigerated chamber. To prevent this the use of a drip pan is indicated, but the presence of a drip pan of ordinarily imperforate construction would so thwart the convection circulation as to make it necessary to run the coil at such a low temperature that it would be covered with frost.

The present invention has for its more specific object the provision of a drip pan extending beneath the coil and being of trap formation whereby the drip from the condenser is caught and drained away while the

maximum degree of space is provided for permitting free convective circulation.

Other objects of the invention will appear as the following description of a preferred and practical embodiment thereof proceeds. 55

In the drawing in which the same characters of reference are used throughout the several figures to designate identical parts:

Figure 1 is a cross section through the top wall of a refrigerated showcase showing the suspended coil and the drip pan;

Figure 2 is a horizontal section taken along the line 2—2 of Figure 1;

Figure 3 is a longitudinal section taken along the line 3—3 of Figure 1; and 65

Figures 4 and 5 are perspective views of the respective end supports for the drip pan at opposite ends of the showcase.

Referring now in detail to the several figures, the numeral 1 represents the top wall 70 of the showcase from which the coil 2 is suspended by suitable means such as the screw eyes 3 fixed to the top wall 1 and supporting a rod 4 which passes beneath a bank of tubes 5 and by means of which the coil is suspended. 75 The coil is preferably of that type known as "cross fin" comprising vertical fins 6 through which pass the horizontal refrigerant tubes 7. The fins of the coil are preferably, although not necessarily, made of aluminum. 80

Figure 3 shows that the coil 2 is designed to extend substantially throughout the length of the showcase along the top of the refrigerated chamber. It will be understood that the air between adjacent fins becoming chilled, 85 will descend, replacing warmer air in the lower part of the refrigerated chamber, which warmer air will ascend to take the place of the cold air, a circulation of air within the refrigerated chamber being thus set up and maintained. Where the entire coil is placed for instance, on one side of the refrigerated chamber, the convection circulation thus set up becomes extremely efficient as has been explained in reference to the objects of the invention. By having the coil extend along the entire top of the refrigerated chamber, it is obvious that the cold air will descend in the center as well as the sides, thus interfering to some extent with the integrity of the convec- 95 100

tion circulation so that it is not so efficient as to permit the coil to be run at a temperature at which moisture condensation will not occur on the fin or top surface of the coil. Consequently, I have provided a drip pan 8 positioned beneath the coil protecting the refrigerated products from the drip of the condenser. This drip pan is preferably constituted by individual members or baffles 9 having web portions 10 only slightly inclined to the vertical, with the lower edges 11 turned up to form a shallow trough and the upper edges 12 angularly bent down in an opposite direction so as just to overhang the troughs 15 of adjacent members.

The drip from the coil falling upon the apex 13 of a baffle member must flow either down the inclined web 10 or down the inclined upper edge, in either event dropping 20 into the trough formed between the web and lower edge of each baffle member.

Figure 3 shows that the baffle members 9 incline toward one end of the showcase so that the moisture flows down the several 25 troughs into a drain channel 14 from which it is carried off through the vent 19.

It will be noted in Figure 1 that the space between adjacent baffle members permits an almost perpendicular descent of the cold air 30 from the surfaces of the coil.

Any suitable means for installing the drip pan are within the broad concept of the invention, but a specific and practical means is herein shown comprising end supports 15 and 25 16 adapted to be secured across the end walls of the showcase within the refrigerating chamber. These supports are of U-shaped cross section as shown, and the inner wall of each support is provided with slots 17 and 18 corresponding to the cross sectional shape of the baffle members except that the slots 18 at their lower portion are enlarged as indicated at 19 providing space for the flow of water through the troughs of the baffle members 40 when the latter are installed in said supports. The baffle members are in length slightly shorter than the distance between the end walls of the refrigerator so that in putting them in place they are first inserted in the 45 slots 18, while in the inclined position indicated in broken lines in Figure 3. They are then pushed as far as possible toward the left as viewed in Figure 3, permitting the right-hand ends to clear the support 15 and 50 to be brought into alignment with the slots 17. The baffle members are then shifted toward the right through the slots 17 until they abut firmly against the outer wall of the support 15. The support 16 which constitutes the drain channel 14 is wider in cross section than the support 15, so that when the baffle members 9 have been shifted as far as possible to the right, they are still engaged by the slots 18 of the support 16.

A suitable latch may be provided to pre-

vent inadvertent displacement of the baffle members which in the present instance comprises a bar 21 having an angular lug 22, by means of which it is pivotally connected to a suitably fixed portion of the showcase. The bar 21 is preferably of angle construction as indicated at 23 in Figure 3, so that when raised it is out of engagement with the baffle members so that they can be shifted leftward for removal if desired. When the bar 21 is in latched position, it rests upon the ends of the baffle members, embracing the ends thereof as shown, so that they cannot be shifted. 75

It is to be understood that the inventive principle concerns itself with the provision of a drip pan adapted to be associated with the refrigerating coil, and so constructed that while it catches all the water dripping from the edges of the fins or from the tubes, yet at the same time, it provides louvers affording a maximum passage for the free circulation of the descending convection currents from the coil. It is to be understood that the specific construction of the baffle members and the specific means for supporting them in the showcase are not essential to the realization of the invention in its broadest aspect, but are merely appurtenant to a specific embodiment of the invention. 80 85 90 95

What I claim is:

1. In a refrigerated showcase, a refrigerating coil in the refrigerating chamber of said showcase in combination with a drip pan beneath said coil, said drip pan comprising spaced parallel members defining substantially vertical passages, the lower edge of each member being formed as a trough, and the upper edge of each member being inclined downwardly to a point intersecting a vertical plane passing through the trough of said adjacent member whereby condensate dripping upon the inclined upper edges of said members is shed into the troughs at the bottom edges of said members. 100 105 110

2. Refrigerated showcase as claimed in claim 1, including supports at the ends of the refrigerating chamber, said supports being of U-shaped cross section defining inner walls and one of said supports being of wider cross section than the other, slots in said inner walls for loosely receiving said members, the slots in one wall being at a lower level than the slots in the other wall whereby said members are inclined toward one support and communicating therewith through its inner wall, said support acting as a drain for said members, said members being of such length that, when shifted to the extent of their range of longitudinal movement toward the support of narrower cross section they will still remain supported at both ends while when shifted to the limit of their range of movement toward the support of wider cross section, they will fall short of reaching the slots in the opposite wall, thereby permitting their 115 120 125 130

introduction into said supports one end at a time.

3. Refrigerated showcase as claimed in claim 1, including supports at the ends of the refrigerating chamber, said supports being of U-shaped cross section defining inner walls and one of said supports being of wider cross section than the other, slots in said inner walls for loosely receiving said members, the slots in one wall being at a lower level than the slots in the other wall whereby said members are inclined toward one support and communicating therewith through its inner wall, said support acting as a drain for said members, said members being of such length that when shifted to the extent of their range of longitudinal movement toward the support of narrower cross section they will still remain supported at both ends while when shifted to the limit of their range of movement toward the support of wider cross section they will fall short of reaching the slots in the opposite wall, thereby permitting their introduction into said supports one end at a time, and a latch engageable with said members for retaining them against displacement when in supported position.

In testimony whereof I affix my signature.
LESTER U. LARKIN.
